MANIFOLDING DEVICE

William G. Borchers, Hoboken, N. J., assignor
to Autographic Register Company, Hoboken,
N. J., a corporation of New Jersey

Application July 16, 1931, Serial No. 551,076

13 Claims. (Cl. 197—133)

This invention relates to manifolding devices for typewriters, and more particularly, to flat bed typewriters such as the Elliott-Fisher book typewriter.

5 An object of this invention is to provide an attachment for such typewriters whereby they may be adapted for use with continuous forms.

In the use of such machines, the long continuous strips of paper, upon which the writing operations are to be performed and which usually each includes a succession of printed forms having aligning apertures at the foot of each form, are stored at the rear of the machine and fed upwardly and forwardly over the typewriter frame to a platen to receive writing operations. At the part of the typewriter nearest the operator, there is provided a tear-off knife so that the written set of forms can be severed from the next adjacent set. At this point also, there is provided a pair of aligning pins to receive the aligning apertures at the foot of each form.

To advance the strips, the operator releases the knife, which also acts to clamp the paper to the platen, grasps the ends of the forms, and pulls the strips through the machine until the next set of apertures reach the aligning pins and are impaled thereon, after which the knife is allowed to again engage the paper and hold it while the written set of forms are torn along the edge of the knife.

Heretofore, it was proposed to provide for each of the strips a mechanical device for drawing the strip back so that the front margins of the apertures will engage the pins and so that the strips will be held taut on the platen.

These individual tensioning devices, in addition to making the device more complicated, make the loading of the machine more involved and difficult for the operator, for each separate strip has to be threaded through its individual back-drag or tensioning device before it is placed on the platen.

Moreover, the active resistance of each tensioning device has to be overcome during the entire advancing movement of the paper strips and the effort which the operator must expend in advancing the strips is accordingly the sum total of the resistances offered by the tensioning device plus the work required to unwind the paper from a spool, or take it off some other source of supply, and lift it to the elevation of the typewriter platen, all of which effort must be continuously expended during the entire paper feeding operation.

55 According to the present invention, the in-

dividual back-drag producing devices are dispensed with, and one single device is used for all of the strips. Moreover, the back-drag device only comes into play when the apertures in the strips are approaching the aligning pins at the delivery side of the typewriter and for the initial advancing movement as they are leaving the pins in the advancing of the next form.

Hence, during the major portion of the strip advancement, the back-drag producing device offers no active resistance to the advancing movement of the paper strips.

A further feature of this invention is the provision of a supporting frame for the attachment so arranged that the back-drag producing device 15 may be adjusted to various positions thereon to accommodate forms of different lengths.

And a still further feature of this invention is the provision of a supporting cradle for a multiple ply spool of webs which, while permanently connected to the attachment, is, nevertheless, supported directly by a structural part of the typewriter frame.

Other features and advantages will herein-after appear.

In the accompanying drawings which illustrate one form of my invention, that is at present preferred—

Figure 1 is a side elevation of a flat platen typewriter with portions of the typewriter frame broken away to show the attachment of the present invention.

Fig. 2 is a fragmentary view of part of the attachment of the present invention, showing the aligning means and the deflector adjusted to different positions from those shown in Fig. 1.

Fig. 3 is a perspective view of a pedestal and writing bed of a book typewriter, showing the present invention applied thereto.

Fig. 4 is a similar view, looking at the device from the front or operator's side.

Fig. 5 is a diagrammatic view showing the positions of the paper strips, tear-off knife, and back-drag and tensioning device of the present invention, during the advancement of a set of forms over the platen and just before the pins of the present invention enter the apertures.

Fig. 6 is a similar view but shows the strips still further advanced and requiring but a short movement to complete the advancement.

Fig. 7 is a view similar to Figs. 5 and 6, but shows the strips as having been impaled on the front aligning pins but not yet released by the operator.

Fig. 8 shows the strips as having been released

by the operator and the written form torn off, the tear-off knife having engaged the strips to hold them during the writing operation.

Fig. 9 is a similar view, showing how the aligning pins of the present invention are automatically released during the beginning of the advancing movement.

Fig. 10 is a sectional view of the rear end of the present attachment, showing the manner in which continuous strips from a zigzag folded pile 10 which continuous strips from a zigzag folded pile are used with the attachment.

The typewriter to which the disclosed embodiment of the present invention is applied is the well known Elliott-Fisher typewriter. It comprises the usual pedestal-like frame 10 supporting tracks or rails 11 between which there is mounted a platen 12 on which worksheet strips 13 are supported in interleaved condition with carbon strips 14 to receive type impressions from a printing device 15 movable back and forth and across the platen.

In this type of machine, the paper strips 13 remain undisturbed on the platen 12 during the writing of a form 16 which is usually printed and 25 of which each strip 13 contains a succession, the spacing between letters and lines being effected by the movement of the printing device 15 over the platen. Consequently, it is only after a set of forms has been written and is ready to be 30 severed from the one following that the strips are advanced.

As usual, the strips 13 are provided with registering apertures 17, two located near the foot of each form, and these apertures are adapted to 35 engage aligning pins 18 at the delivery side of the platen to locate the strips in proper position on the platen and to register the strips relative to one another. The strips 13 are held on the aligning pins 18 by a bar 19, the front 20 of which 40 has a knife edge along which the strips are torn to sever a written set of strips from the set following. The tear-off knife 19 is pivotally mounted so that it may be moved from the position shown diagrammatically in Fig. 8, to those shown 45 in Figs. 5, 6, 7 and 9, so as to allow the adjacent edges of a set of strips to be grasped by hand and lifted off the pins 18 to be drawn forwardly or toward the operator until the next set of apertures 17 is over the aligning pins 18, whereupon 50 the tear-off knife is allowed to descend and grip the strips so that they may be torn off along the knife edge 20.

With such devices, it was heretofore proposed to provide a tension and back-drag producing device for each one of the strips 13 so that after the strips were impaled upon the pins 18, they would each be drawn back separately to bring the edges of the apertures 17 against the front edges of the pins and to keep the strips 55 taut on the platen 12 during the writing operation. With this arrangement, however, it was necessary that the active resistance of each of the tensioning and back-drag producing devices had to be overcome by the operator during the 60 entire advancing movement of the strips. It was also necessary, in preparing the machine for use with a new supply of paper, to thread each individual strip through its own tension and back-drag producing device.

70 An object of the present invention is to provide a tensioning and back-drag producing device common to all of the strips and through which the strips may be passed as a whole in superposed condition in loading the machine.

75 Another object of this invention is to provide a

back-drag producing device which does not actively resist paper advancement by the operator during the major portions of the advancing of the strips but only just before a fresh set of forms reaches its writing position and just at the beginning of the next paper advancing operation, thereby avoiding the work and accompanying fatigue attendant upon the advancement in the prior proposals having individual back-drag producing devices for each strip which offer active resistance to the strips for the entire paper advancing movement.

These objects of the present invention are attained in an extremely simple and expeditious manner, and for this purpose the present invention provides at the introductory side of the platen 12 a pair of pins 21 mounted on a shaft 22 having bearings in side plates 23 of the frame of the attachment. The shaft 22 is mounted for oscillatory movement and has an arm 24 connected 20 to a spring 25 having its other end anchored by screws 26 in the side plates 23. The spring 25 normally tends to rock the shaft 22 so that the pins 21 are directed rearwardly as shown in Figs. 1 and 5, and will be in position to enter the 25 aligning apertures 17 in the strips 13 as the strips are advanced.

If the strips 13 approach the pins 21 in an upwardly direction, the weight of the depending portions of the strips behind the strips will cause 30 the strips to be urged toward the pins so as to fall onto the shaft 22 when the pins 21 enter the apertures 17. However, since it is not always possible to have the strips so approach the pins 21, the present invention provides a deflector bar 35 27 directly to the rear of and below the shaft 22 and pins 21 to cause the path of the strips to be tortuous over the pins 21. Hence, the tendency of the strips to straighten out when pulled forwardly will cause the strips to be pulled down on 40 the pins 21 so that they will enter the approaching apertures 17, as shown in Fig. 6.

When this occurs, the continued advancement of the strips causes the shaft 22 to be rocked by dragging the pins along with the strips and this 45 continues until the apertures 17 at the delivery end of the platen extend over the aligning pins 18, as shown in Fig. 7, at which time the advancing operation is completed and the knife bar 19 is allowed to descend toward the platen. However, before the knife 19 reaches the platen to 50 grip the strips 13, the strips are released by the operator and are all drawn back by the pins 21 due to the fact that the spring 25 tends constantly to rock the shaft and pins in a counter-clockwise direction, as viewed in Figs. 5 to 9. This retrograde movement of the strips causes the leading edges of the apertures 17 to be brought into firm contact with the forward surfaces of the pins 18 and stretches the strips tightly 55 on the platen, so that they will be held in this position during the writing operation. When the knife bar 19 has reached the position shown in Fig. 8, the written set of forms is drawn upwardly over the knife edge 20 to sever them from the 60 portions of the strips impaled on the pins 18.

After the set of forms has been written upon and when it is desired to advance it to be severed, the operator raises the knife bar 19, lifts the leading edges of the strips off the pins 18, and pulls them forwardly. During this movement, the pins 21 are carried forwardly by the set of apertures 17 which they engage until they have swung so far that the apertures are free from the pins. This having been done, the spring 25 draws the pins 75

21 backwardly under the pile of strips to the position shown in Fig. 5, where the pins are ready to engage the next set of registering apertures 17, and this movement of the pins is facilitated by 5 the rear sides of the pins being tapered off.

In addition to the advantages above referred to, by having the strips suddenly, yet gently and yieldingly impaled on the pins 21 just as the end of the advancing movement is approached, the 10 operator, feeling the added resistance, becomes aware that the full form-length is almost completely advanced and may therefore continue the rest of the advancing means more slowly and carefully so as not to over-draw the strips too far. 15 Of course, the extent of withdrawal movement of the strips in the device of the present invention is not critical, and should the strips be overdrawn a little too far, the pins 21 will draw them back to the proper position shown in Fig. 7.

20 With the device of the present invention, the location of the pins 21 is, of course, preferably a form-length or a multiple thereof from the pins 18 so that the same apertures 17 may be used on both the pins 21 and the pins 18. Therefore, 25 in order that the attachment may be used with any of the various standard length forms, the side plates 23 are provided with spaced bearings 22 for the ends of the shaft 22 and spaced tapped holes 29 for the screws 26 which anchor one end 0 of the spring 25. In addition to this, the frame plates 23 have holes for a tie rod 31 which is employed to prevent spreading of the frame near the place where the shaft 22 is journaled. The frame has also tapped holes 32 for a stop screw 5 33 which limits the rearward movement of the pin shaft 22.

The pins 21 are so shaped at their rear sides that when they have been swung forwardly, as shown in Fig. 9 and are disengaged by the apertures, they very easily cam up the pile of strips and move to their rearward position, shown in Fig. 5.

In the broader aspects of this invention, the paper may be supplied to the device in any suitable way, and it may be either rolled or folded. As shown in Figs. 1 and 3, the paper strips 13 are wound on a single spool 34. According to the present invention, this spool is supported in a cradle comprising side arms 35 and upper and lower tie rods 36. The side arms have notches 37 into which a shaft 38 for the spool 34 may pass to be supported thereby. The upper end of the cradle is connected to the side plates 23 of the attachment by screws 39, but is, however, not supported thereby. It is instead supported on a cross rod 40 of the typewriter frame having for this purpose hook-shaped portions 41, one on each of the arms 35.

The multiple ply spool 34 is kept from casual unwinding by a weight bar 42 slidably mounted in slots 43 in the side arms 35 of the cradle. This weight bar 42 has reduced end portions fitting the slots 43 and does not turn but merely slides over the surface of the spool 34 of paper, and in this way offers sufficient resistance to the turning movement of the spool to prevent the spool from being unwound too rapidly as the paper is drawn herefrom.

The strips of paper after leaving the spool 34 extend upwardly and forwardly to pass over the pin shaft 22.

The device of the present invention is also well adapted for use with folded stationery such as the zig-zag folded pack 34a shown in Fig. 10, such a pack is supported on the end of a table,

or some other suitable support, so that the strips coming from the back may extend upwardly to the attachment. When folded stationery is used, it is preferable that instead of the strips passing directly to the pin shaft 22, they extend upwardly 5 over the guide bar 46 located at the rear end of the machine. The pack 34a is located under this guide rod so that when the strips are being advanced, they will not inadvertently pull several layers off the pile. The use of the guide rod 46 10 also insures that the strips will, after passing under the deflector 27, extend upwardly and forwardly over the pin shaft 22 to have its apertures engaged by the pins 21.

To guide the strips laterally, the guide bar 15 46 and the pin shaft 22 may, as illustrated herein, be provided with flanged collars 45.

At its front end, the frame of the attachment is provided with a lug 46 extending over a structural part 47 of the typewriter to support the 20 attachment thereon. At the rear, the attachment is supported by the tie rod 40 of the typewriter engaging the hook-shaped portions 41 of the cradle which in turn is fastened to the plates 23 by the screws 39. To keep the frame down 25 on these parts, each side plate 23 is provided with an angular clamping member 48 which engages the end portions of the rails 11 and is secured in place to the frame by a wing nut 49.

Variations and modifications may be made 30 within the scope of this invention and portions of the improvements may be used without others.

Having thus described the invention, what is claimed as new and for which it is desired to obtain Letters Patent, is:

1. A typewriter having a platen over which a plurality of worksheet strips is advanced form-length extents to bring a fresh form to writing position thereon and having aligning pins at the delivery side of the platen for engagement with aligning holes provided at form-length intervals in the worksheet strips, a rotatable shaft with a pair of aligning pins located at the rear of introductory side of the platen on which pins the worksheet strips normally ride engaging the same solely by gravity and travel without active resistance therefrom until the apertures in the strips are entered by the pins, said rear aligning pins being mounted for rotary movement in the direction of strip travel and being moved by only the strips during the final advancing movement thereof, said rear aligning pins being located with respect to the aligning pins at the delivery side of the platen so as to remain in engagement with the aligning apertures just 45 before, while, and just after, another set of apertures is in a position to engage the aligning pins at the delivery side of the platen, said rear aligning pins being normally urged to move in a direction counter to the advancing movement of the strips and imparting to the strips when engaged in the apertures a tendency toward retrograde movement to tension the strips while the strips are held on the aligning pins at the delivery end of the platen.

2. A typewriter having a platen over which a plurality of worksheet strips is advanced form-length extents to bring a fresh form to writing position thereon and having aligning pins at the delivery side of the platen for engagement with aligning holes provided at form-length intervals in the worksheet strips, a pair of intercepting and aligning pins located at the rear or introductory side of the platen over which the worksheet strips normally travel without active 70 75

resistance until the apertures in the strips are entered thereby, said rear aligning pins being mounted for movement in the direction of strip travel and being moved by only the strips during the final advancing movement thereof, said rear aligning pins being located with respect to the aligning pins at the delivery side of the platen so as to remain in engagement with the aligning apertures just before, while, and just after, another set of apertures is in a position to engage the aligning pins at the delivery side of the platen, said rear aligning pins being normally urged to move in a direction counter to the advancing movement of the strips and impeding the strips when engaged in the apertures a tendency toward retrograde movement, said rear pins being disengaged from the apertures in the strips by the initial advancing movement of the strips and when free from the apertures moving rearwardly under the strips to a position subsequently to engage the next set of apertures.

3. A typewriter having a platen over which a plurality of worksheet strips is advanced form-length extents to bring a fresh form to writing position thereon and having aligning pins at the delivery side of the platen for engagement with aligning holes provided at form-length intervals in the worksheet strips, comprising a single set of aligning pins at the introductory or rear side of the platen released from the strips solely by movement of the strips.

4. A typewriter having a platen over which a plurality of worksheet strips is advanced form-length extents to bring a fresh form to writing position thereon and having aligning pins at the delivery side of the platen for engagement with aligning holes provided at form-length intervals in the worksheet strips, comprising a single set of aligning pins at the introductory or rear side of the platen, said rear aligning pins being mounted for oscillation to be released from the strips solely by movement of the strips and being normally urged rearwardly to impart to the strips a tendency toward retrograde movement when engaged with the aligning apertures in the strips.

5. A typewriter having a platen over which a plurality of worksheet strips is advanced form-length extents to bring a fresh form to writing position thereon and having aligning pins at the delivery side of the platen for engagement with aligning holes provided at form-length intervals in the worksheet strips, comprising a single set of aligning pins at the introductory or rear side of the platen, said rear aligning pins being mounted for oscillation to be released from the strips solely by movement of the strips and being normally urged rearwardly to impart to the strips a tendency toward retrograde movement when engaged with the aligning apertures in the strips, and means adjacent the rear aligning pins at the introductory side of the platen for causing the worksheet strips to follow a tortuous path intercepting the arc of movement of the pins whereby the pins are caused to enter the apertures as a result of the tendency of the strips to straighten their paths as the strips are being advanced over the platen.

6. A typewriter having a platen over which a plurality of worksheet strips is advanced form-length extents to bring a fresh form to writing position thereon and having aligning pins at the delivery side of the platen for engagement with

7. A typewriter having a platen over which a plurality of worksheet strips is advanced form-length extents to bring a fresh form to writing position thereon and having aligning pins at the delivery side of the platen for engagement with aligning holes provided at form-length intervals in the worksheet strips, comprising a single set of aligning pins at the introductory or rear side of the platen; a shaft on which said rear pins are mounted for oscillatory movement to be released from the strips solely by movement of the strips; a deflector adjacent said shaft and tending to cause the strips to be urged toward the rear pins in their advancing movements; a frame attachable to the typewriter frame in which said shaft and deflector are mounted, said frame having spaced bearings for the shaft and deflector to permit the positions of the latter to be varied with relation to the positions of the pins at the delivery side of the platen to accommodate forms of different lengths.

8. A manifolding device having a platen over which a plurality of worksheet strips is advanced form-length extents to bring a fresh form to writing position thereon, the worksheet strips having apertures at form-length intervals; a rotatable shaft; a pair of aligning pins on said shaft located at the introductory side of the platen on which pins the worksheet strips rest and engage solely by gravity and travel without active resistance from the pins until the apertures in the strips are entered by the pins, said aligning pins being mounted for rotary movement in the direction of strip travel and being moved by only the strips during the final advancing movement thereof, the aligning pins being so located that they are in engagement with the aligning apertures in the strips just before, while, and just after, the strips reach writing position, said aligning pins being normally urged to move in a direction counter to the advancing movement of the strips and imparting to the strips when engaged in the apertures a tendency toward retrograde movement.

9. A manifolding device having a platen over which a plurality of worksheet strips is advanced form-length extents to bring a fresh form to writing position thereon, the worksheet strips having apertures at form-length intervals; a pair of aligning pins located at the introductory side of the platen on which pins the worksheet strips rest by gravity and travel without active resistance from the pins until the apertures in the strips are entered by the pins, said aligning pins being mounted for movement in the direction of strip travel and being moved by the strips alone during the final advancing movement thereof, the aligning pins being so located that they are in engagement with the aligning apertures in the strips just before, while, and just after, the strips reach writing position, said aligning pins being normally urged to move in a direction counter to the advancing movement of the strips and imparting to the strips when engaged in the apertures a tendency toward retrograde

movement, the aligning pins being disengaged from the apertures in the strips by the initial advancing movement of the strips and when free from the apertures moving rearwardly under the strips to position subsequently to engage the next set of apertures.

10. A manifolding device having a platen over which a plurality of worksheet strips is advanced form-length extents to bring a fresh form to writing position thereon, the worksheet strips having apertures at form-length intervals; and a single set of aligning pins at the introductory side of the platen positioned to intercept the apertures of the strips and to be released therefrom by the movement of the strips.

11. A manifolding device having a platen over which a plurality of worksheet strips is advanced form-length extents to bring a fresh form to writing position thereon, the worksheet strips 20 having apertures at form-length intervals; and a single set of aligning pins at the introductory side of the platen, said aligning pins being mounted for oscillation to be released from the strips solely by movement of the strips and being normally urged rearwardly to impart to the strips a tendency toward retrograde movement when engaged with the aligning apertures in the strips, and means adjacent said pins for causing the worksheet strips to follow a tortuous path intercepting the arc of movement of the pins 10 whereby the pins are caused to enter the apertures as a result of the tendency of the strips to straighten their paths as the strips are being pulled over the platen.

12. A manifolding device having a platen over which a plurality of worksheet strips is advanced form-length extents to bring a fresh form to writing position thereon, the worksheet strips having apertures at form-length intervals; and

a single set of aligning pins at the introductory side of the platen, said aligning pins being mounted for oscillation to be released from the strips solely by movement of the strips and being normally urged rearwardly to impart to the strips a tendency toward retrograde movement when engaged with the aligning apertures in the strips, and means adjacent said pins for causing the worksheet strips to follow a tortuous path intercepting the arc of movement of the pins 10 whereby the pins are caused to enter the apertures as a result of the tendency of the strips to straighten their paths as the strips are being pulled over the platen.

13. A manifolding device having a platen over which a plurality of worksheet strips is advanced form-length extents to bring a fresh form to writing position thereon, the worksheet strips having apertures at form-length intervals; and a single set of aligning pins at the introductory 20 side of the platen, a shaft on which said pins are mounted for oscillatory movement to be released from the strips solely by movement of the strips, a deflector adjacent said shaft and tending to cause the strips to be urged toward the pins in 25 their advancing movements, a frame in which said shaft and deflector are mounted, said frame having spaced bearings for the shaft and deflector to permit the positions of the latter to be varied with relation to the introductory side of the platen 30 to accommodate forms of different lengths.

WILLIAM G. BORCHERS.
